DESIGN FOR A CAMERA

Douglas F. Hawkins, Los Angeles, and William A. Moore, West Hollywood, Calif., assignors to Wm. R. Whittaker Co., Ltd., Los Angeles, Calif., a corporation of California

Application March 10, 1947, Serial No. 137,476

Term of patent 14 years

(Cl. D61—1)

To all whom it may concern:

Be it known that we, Douglas F. Hawkins and William A. Moore, both citizens of the United States, the former residing at Los Angeles, in the county of Los Angeles and State of California, and the latter residing at West Hollywood, in the county of Los Angeles and State of California, have invented a new, original, and ornamental Design for a Camera, of which the following is a specification, reference being had to the accompanying drawing, forming part thereof, in which:

Fig. 1 is a top view of a camera, showing our new design;

Fig. 2 is a view of one end;

Fig. 3 is a front view;

Fig. 4 is a view of the other end;

Fig. 5 is a bottom view; and

Fig. 6 is a rear view thereof.

We claim:

The ornamental design for a camera, as shown.

DOUGLAS F. HAWKINS.

WILLIAM A. MOORE.
